(57) **CLAIM**

The ornamental design for a connecting terminal for storage battery, as shown and described.

DESCRIPTION

FIG. 1 is a perspective view of the front, left and top sides of a connecting terminal for storage battery showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a reference view of usage thereof.

The broken lines shown represent environmental subject matter only and form no part of the claimed design.
